[57] CLAIM

The ornamental design for an food package, as shown and described.

DESCRIPTION

FIG. 1 is a top plan view of a food package showing my new design;

FIG. 2 is a front elevation thereof; the rear elevation being a mirror image thereof;

FIG. 3 is a right side elevation thereof; the left side elevation being a mirror image thereof;

FIG. 4 is a perspective view thereof;

FIG. 5 is a perspective view thereof; with the right side end in open position; and

FIG. 6 is a perspective view thereof; with the left side end in open position.

The solid lines shown in side elevations and perspective views represent cut lines. The essential feature of my design resides in the particular tearstrip shown.

FIG 1.FIG 2.FIG 3.FIG 4.FIG. 5.FIG. 6.
